CLAIM

What is claimed is the ornamental design for an electric comb, as shown and described.

DESCRIPTION

FIG. 1 is a front perspective view of the electric comb. FIG. 2 is a front elevation view of the electric comb, the rear elevation view being a mirror image thereof. FIG. 3 is a left side elevation view thereof. FIG. 4 is a right side elevation view thereof. FIG. 5 is a top plan view thereof; and, FIG. 6 is a bottom plan view thereof. The broken lines shown in the drawings illustrate portions of the electric comb that form no part of the claimed design.
